UNITED STATES PATENT OFFICE

2,510,988

CUFF FASTENER

Jackson B. Lewis, Los Angeles, Calif.

Application February 13, 1946, Serial No. 647,297

3 Claims. (Cl. 24—102)

1

This invention relates to novel and useful improvements and structural refinements in cuff fasteners, and the principal object of the invention is to provide a device of the character herein described which is particularly adapted for use with shirts and the like, the cuffs of which are provided with the conventional buttons and button-holes.

A further object of the invention is to provide a cuff fastener which is of yieldable character, whereby the cuffs may be fastened before the shirt is worn and which will expand sufficiently to allow the passage of the arms through the cuffs when the shirt is subsequently put on.

Another object of the invention is to provide a cuff fastener, which, by virtue of the advantage set forth in the preceding paragraph, will allow the shirt sleeves to be pulled upwardly on the arms while washing or working, without the necessity of unfastening the cuffs.

An additional object of the invention is to provide a cuff fastener which is of pleasing appearance.

A still further object of the invention is to provide a cuff fastener which is of simple construction and which will not easily become damaged.

With the above more important objects in view and such other objects as may become apparent as this specification proceeds, the invention consists essentially of the construction and arrangement of parts as shown in the accompanying drawings, in which:

Figure 1 is a perspective view of the invention, Figure 2 is a plan view thereof,

Figure 3 is a side elevation of the same, and

Figure 4 is a perspective view illustrating the invention applied to a shirt cuff.

Like characters of reference are used to designate like parts in the specification and throughout the several views.

Referring now to the accompanying drawings in detail, the invention consists of an anchoring button 5 provided on one side thereof with an eye 6. This button may assume any convenient form, and the remaining side thereof may be engraved or otherwise ornamentally inscribed in order to enhance the appearance of the fastener.

A safety pin 8, provided with the conventional, releasable side 9, has a bend 10 formed in the fixed side 11 thereof. This bend constitutes a keeper seat which will also be referred to herein-after by the reference numeral 10.

A tension spring 12 is formed at each end thereof with a loop 13, whereby it may be connected at one side to the aforementioned eye 6

2

while the remaining end thereof is engageable with the keeper seat 10.

The loops 13 are also connected by means of a chain 14 which is somewhat longer than the compressed length of the spring 12, and the purpose of which will be hereinafter more particularly described.

When the invention is placed in use, the anchoring button 5 is placed against the outer surface 15 of one side of the cuff 16, with the eye 6 extending into the button-hole 17. The releasable arm 9 of the safety pin 8 is then fastened on the inner surface 18 of the remaining side of the cuff, adjacent to the conventional button 19.

15 The fastening as above described may be performed before the shirt is worn, and when the same is subsequently put on, the spring 12 will stretch sufficiently to permit the arms to be inserted and passed through the cuffs 16. At the 20 same time, the chain 14 will prevent over-stretching of the spring, which may otherwise result if the arms are not passed through the cuff with care.

When the shirt is worn, the spring 12 will similarly allow the sleeves to be pulled upwardly on the arms while washing or working, without the necessity of unfastening the cuffs.

It is thought that persons skilled in the art to which the invention relates will be able to obtain a clear understanding of the invention after considering the description in connection with the drawings. Therefore, a more lengthy description is regarded as unnecessary.

35 Minor changes in the shape, size and arrangement of details coming within the field of invention claimed may be resorted to in actual practice, if desired.

What I claim as my invention is:

40 1. An expansible cuff fastener comprising a button, a coil spring having opposing loop ends, one of said ends being secured to the button, a safety pin, the other of said loop ends being secured to the pin, said spring being connected transversely between the button and the pin, and a flexible stop member connected between the loop ends of the spring and limiting the expansion thereof.

45 2. An expansible cuff fastener comprising a button, a coil spring having opposing loop ends, an eye on one side of the button, one of said loop ends being secured to the eye, a safety pin, the other of said loop ends being secured to the pin, and a flexible stop element connected between the loop ends of the spring and limiting the expansion thereof.

3. An expandible cuff fastener comprising a button having an eye formed on one side thereof, a coil spring having opposing loop ends, one of said loop ends being secured to the eye, a pin having a fixed section and a movable section, the other of said loop ends being attached to the fixed section, means for centering the loop end thereon and a flexible stop member connected between the opposing loop ends of the spring for limiting the expansion thereof.

JACKSON B. LEWIS.
